UNITED STATES PATENT OFFICE.

SAMUEL DONAHEY, OF CHICAGO, ILLINOIS.

DESIGN FOR A BRIDLE-HOLDER.

SPECIFICATION forming part of Design No. 25,613, dated June 9, 1896.

Application filed May 1, 1896. Serial No. 589,912. Term of patent 14 years.

To all whom it may concern:

Be it known that I, SAMUEL DONAHEY, a citizen of the United States, residing at Chicago, in the county of Cook and State of Illinois, have invented and produced a new and original Design in Bridle-Holders, reference being had to the accompanying drawing, forming a part hereof.

In the accompanying drawing the figure is
10 a perspective view of my design.

The leading feature of my design consists in a semicircular main portion provided with notched flange at one lateral edge and projecting portion at the opposite lateral edge.

A is the semicircular main portion; B, the 15 flange at the front lateral edge, provided with a notch *b*, and C the projections at the opposite lateral edge, the whole presenting to the eye a harmonious and ornate figure, as shown in the accompanying drawing. 20

I claim—

The design for a bridle-holder substantially as shown and described.

SAMUEL DONAHEY.
